COMBINED PEG HEAD, NECK AND FINGER BOARD OF A GUITAR OR SIMILAR ARTICLE

Charles A. Gauvin, 805 S. Water St.,
Silverton, Oreg. 97381

Filed Nov. 15, 1965, Ser. No. 88,093

Term of patent 14 years

(Cl. D56—1)

FIG. 1.

FIG. 2.

FIG. 3.

FIG. 4.

FIG. 1 is a front elevational view of a combined peg head, neck and finger board of a guitar or similar article, showing my new design;

FIG. 2 is a left side elevational view;

FIG. 3 is a top and left side perspective view; and

FIG. 4 is a cross sectional view, to an enlarged scale taken on line 4—4 in FIG. 1.

I claim:

The ornamental design for a combined peg head, neck and finger board of a guitar or similar article, substantially as shown.
